UNITED STATES PATENT OFFICE

2,381,811

FIRE ESCAPE APPARATUS

Harland D. Elwood, Detroit, Mich., assignor to
Lewis A. Eastman, Wyandotte, Mich.

Application July 21, 1943, Serial No. 495,615

4 Claims. (Cl. 227—39)

This invention relates to fire escape apparatus and particularly to devices of that class, which may be attached in permanent or semi-permanent manner, to the interior of a building, and are ready for instantaneous use when the need arises.

An object of the invention is to provide a fire escape device, which is simple in construction, inexpensive to manufacture, and one which may be stored inside a building in an inconspicuous and compact space near a window or other wall opening.

Another object of the invention is the provision of a fire escape apparatus which may be folded and stored in a wall cabinet, and then quickly swung into operative position for use.

A further object of the invention is the provision of a device which employs a novel means for anchoring a flexible fire escape chute in position for ready access.

The foregoing, and other objects and advantages of the invention will appear as the description proceeds, reference being made from time to time to the accompanying drawing in which:

Fig. 1 is a perspective view of a device embodying my invention.

Fig. 2 is a view showing the device in adjusted position before a window.

Fig. 3 is a perspective view showing the chute extending from the window to the ground anchors.

Fig. 4 is an enlarged detail showing the chute supporting means and the device in position in a window.

Referring now more particularly to the drawing it will be understood that in the embodiment herein disclosed, my device consists generally of a pivotable supporting frame 10, and a flexible chute 11, which when not in active use is stored in folded condition in a wall cabinet 12. The cabinet 12 is supported by a wall bracket 13 and is provided with a slidable drop front cover 14, which in turn is locked in closed position by any suitable means, 15. The wall 16 of the cabinet is slotted as at 17, to permit the frame supporting arm 18 to clear, when the device is in storage, as shown in Fig. 1. The frame supporting arm 18 is secured by a T 19, to a suitable vertical member 20, which telescopes into the pipe 21, which in turn is flanged to the floor as at 22, and to the wall as at 23 and 24. A bearing member 25 permits the vertical member 20 and the arm 18, to pivot with greater ease.

Secured to the outer end of the arm 18, by suitable means such as the T 26 and elbow 27

(Fig. 1) are the uprights 28 and 29 to each of which is pivoted as at 30, a wing 31, which is provided with means 32, for securing thereto the sides 33 of the flexible chute 11. U-shaped members 34, are welded or otherwise secured to the arm 18, adjacent the lower ends of the uprights 28 and 29, and serve as sockets for the bar 35 which engages a terminal loop 36 formed in the bottom of the chute 11. The bar 35 is held against accidental displacement by means of the bolts 37, which extend through the legs of the U-shaped sockets 34.

When not in use the wings 31 are swung back parallel to one another, as shown in Fig. 2, and the chute is folded and secured in position by the strap 38.

When occasion arises for need to use the device the cover 14 is dropped, and the arm 18 is swung outwardly so that the folded chute 11, the uprights 28 and 29, and the wings 31 are all disposed in the window opening so that the thrust is carried by the arm 18 which rests against the wall. The strap 38 is then unfastened and the chute 11 is allowed to unfold by its own weight toward the ground, where an assistant secures the loose end of the chute to the posts 39, (Fig. 3) or other suitable anchoring elements, by means of the cables 40, (Fig. 4) which run through tunnels formed in the upper edges of the sides 33 of the chute 11, and are secured to the wings 31 as at 32a.

The device is now ready for the evacuation of persons from the building.

Having described my invention what I claim and desire to secure by Letters Patent is:

1. In a device of the character described, the combination of a flexible chute, an arm, a pivot support for said arm, uprights adjacent the free end of said arm, wings pivoted to said uprights, said wings being adapted to support the sides of said chute, a removable bar mounted between said uprights and adapted to support the bottom of said chute, and a housing adapted to accommodate said uprights, wings, and said chute, when the latter is folded, said housing having a slot in one side arranged to accommodate said arm.

2. The combination of a wall cabinet positioned a predetermined distance from a wall opening, a wall opening, an arm adapted to pivot so that its free end may extend into said cabinet in one position and be in alignment with said wall opening in another position, matched uprights on said arm, and chute supporting means on said uprights.

3. The combination defined in claim 2, in which the chute supporting means include a pair of rotatable wings, there being a flexible chute attached to said wings, said chute being folded when the end of said arm is in said cabinet, and said chute being extended through said wall opening when the said arm is in alignment with said wall opening.

4. In a device of the character described, the combination of a wall cabinet positioned a pre-determined distance from a wall opening, a flexible chute in said cabinet, a supporting frame for said chute, and an arm adapted to support said frame, said arm being adapted to move said chute from said wall cabinet to said wall opening.

HARLAND D. ELWOOD.
